RUG HOLDER

Elmer Clarence Schacht, Troy, N. Y., assignor to
 Behr-Manning Corporation, Troy, N. Y., a corporation of Massachusetts

Application December 21, 1932, Serial No. 648,251

39 Claims. (Cl. 154—49)

This invention is an article to prevent the slipping of rugs, floor coverings or similar materials, on polished floors or other surfaces, which consists of a separate layer placed between the rug 5 and the floor and comprising sheet material having frictional contact surfaces and which is flexible, resilient and in some cases hygroscopic. Throughout this application the subject article will be called a rug holder.

10 The rug holders as hereinafter described perform the functions of preventing the slipping of the rugs on the rug holder and the rug holder on the floor, with the result that there is no movement of the rug relative to the holder or the holder relative to the floor or both the rug and holder relative to the floor. In other words, there exists a cooperative relationship between the rug on one side of the holder and the floor on the other side, so as to prevent relative movement 15 between their contiguous surfaces. The rug holder will preferably be reversible having interchangeable frictional contact surfaces, although in some cases it is provided with a frictional contact surface on one side only.

20 Rug holders find their principal use under small household rugs, commonly called scatter size rugs, which are placed directly upon polished floors. Such rugs when unaccompanied by rug holders present a serious safety hazard in that 25 their slipping causes people to fall which often results in serious personal injuries. Also, such unsafeguarded rugs become constantly disarranged, which produces an untidy appearance in the household. When curled, wrinkled, folded or otherwise disarranged, they present an added 30 hazard due to their tendency to cause people to trip or stumble and fall.

35 The rug holder of this invention prevents the slipping of the rug and keeps the rug lying flat which overcomes the difficulties described above. By keeping the rug flat, destructive folding and wrinkling are eliminated, which greatly prolongs the length of life of the rug. In addition the flat-lying feature facilitates sweeping and vacuum 40 cleaning operations. The rug holder has also been found to increase the suction of vacuum cleaners which improves their cleaning efficiency.

45 The rug holder of this invention comprises a base or sheet material which consists of a web of fibres, a web of separators and fibres or other fibrous sheet material or cloth or any textile or fabric structure. This base is saturated and/or coated with a flexible binder. In one form this flexible binder may be for example, glue, glycerine and formaldehyde, which will preserve, enhance 50

or contribute to the strength, flexibility and resilience of the finished product and make it hygroscopic. A preferred form consists of a fibre-separator (e. g., cork) base saturated, and also preferably coated, with a rubber composition of the character hereinafter described. I prefer both to saturate and coat, so that the surfaces have frictional qualities imparted by both the cork and the rubber, and as a rubber composition I find very satisfactory a latex having 55 combined therewith suitable vulcanizing agents, accelerators, activators and antioxidants. This embodiment of my invention is particularly useful in dry atmospheres where other forms utilizing hygroscopic properties, resulting from other types of saturants, may lose some of their effectiveness. While this rubber-saturated type of rug holder does not have the hygroscopic property hereinafter described, I have found that it does have the other properties and advantages set 20 forth. In fact, it actually has improved or superior qualities which do not vary with humidity conditions.

25 In some cases the base material is saturated and/or coated with a flexible binder which is 25 hygroscopic, such as glue, glycerine and formaldehyde, or with a non-hygroscopic binder, for example, rubber, by which binders resilient particles, such as comminuted cork, are affixed to one or both sides of the holder. A sizing or top coating 30 of one of the flexible binders is applied in some cases to more firmly secure the particles to the base. Another method of producing resilient surface irregularities is by embossing, corrugating, perforating, or similarly processing the saturated 35 and/or coated base material. Both of these methods just described endow the surface of the rug holder with a tentacular capacity and a multiplicity of minute vacuum cups and a multitude of resilient protuberances or protrusions or irregularities of surface level which will extend into and resist movement through or over the irregularities of surface level of contiguous material.

40 As a specific example of a very satisfactory rug holder, I employ a base consisting essentially of a paper-like web comprised of separators, such as comminuted cork and fibre and saturated with a flexible hygroscopic binder, such as tanned glue and glycerine. A rug holder of this type 45 possesses all of the necessary attributes, namely, strength, flexibility, and resilience, and at the same time is hygroscopic. As another specific example of a rug holder, according to my invention, I provide a paper-like web formed of alpha- 50

cellulose fibres, for example, and separators, e. g., cork, and this web I saturate with a rubber composition of the character hereinafter described. I also preferably apply a thin coating of a rubber 5 composition to the surfaces after saturation. In both forms of the invention the anti-slipping qualities are enhanced by the presence on the surface of a high percentage of resilient cork particles forming a particulated frictional contact surface. This web is produced by a paper-making process as described in my U. S. Patents 1,888,409 and 1,888,440, issued November 22, 1932, and has included therein a flexible binder.

The paper-like web of this development is likewise made on a paper-making machine of the cylinder, single Fourdrinier, or multiple Fourdrinier type. A stock consisting of the fibres and separators is prepared and formed into a paper-like web in the usual manner. The web so produced has included therein a flexible binder preferably by saturating in a bath.

The fibres with which the separating particles are mixed to form the web should be sufficiently long (a) to contribute tearing strength to the finished product (b) to mesh and hold the "separating particles", i. e., the cork, and (c) to make an absorbent paper, quickly permeable to saturating solutions. Specific examples of the fibres which I employ are:

30	Jute	Absorbent alpha cellulose
	Rope	Wood pulp fibres
	Hemp	Cotton
	Sisal	Linen
35	Kraft pulp fibres	Asbestos
	Long wood pulp fibres	

By separators, I mean materials of low specific gravity which are compressible and/or elastic, which preferably can be screened to a size and 40 which are of a character which retain compressibility and size when wet or compressed and which continue to separate the contiguous fibres and tend to cause these fibres to return to their original position when pressure has been 45 released. Another example of a separator, in addition to comminuted cork, is granulated rubber.

The relative proportions of cork and fibre in the stock fed to the paper-making machine can be varied and controlled. I have successfully 50 used three parts of fibre to one part of cork by weight and have also used up to three parts of cork to one part of fibre by weight.

As the separator, I prefer comminuted cork which should be of a size which may be termed 55 "effective". That is to say, the cork granules to be effective should not exceed, in cross section, the desired thickness of the finished sheet, nor should they be smaller in cross-section than the cross-sectional diameter of the fibres. Finer cork 60 than this will act as a filler, thereby preventing the formation of voids and air cells, and also will be lost to a larger extent in the paper-making process; likewise smaller particles would be ineffective in acting as separators and hinges about 65 which the fibres can flex. I have used successfully cork particles of a grade from 24 to 150 mesh. Preferably, the cork particles are graded, so that a substantial percentage is in the coarse sizes, namely 24 to 50 mesh, whereby the particulated surface is produced.

By a particulated surface, I mean formation of surface irregularities due to the presence of small particles of frictional material on the rug holder surface. These particles may be incorporated in the sheet material, for example a

paper-like web, at the time of formation of such a sheet, or subsequently affixed to the surface of a sheet by means of a coating.

Paper-like webs obtained by the combination of fibres and separators as above set forth, before saturation have the characteristics of strength and compressibility, but tend to crack or exhibit weakened areas if sharply flexed or creased. In other words, this product will have a tendency toward brittleness and will not possess a flexibility or resiliency comparable to the saturated material.

In order to obtain a satisfactory finished product for rug holder use, I permeate the web by permanently and insolubly incorporating therein any suitable flexible binder.

The binder is preferably incorporated by means of a saturating bath. The cork fibre paper-like web made on the paper-making machine is passed through a tank containing, for example, a solution of glue and glycerine and water. 20 Thereafter, the web is passed through a cooling zone, to jell the glue but not freeze it, and from there is passed through a bath containing a tanning agent, such as formaldehyde. The web is dried by festooning on drying racks or in any other suitable manner. The binder creates a stronger union between the fibres and cork particles, increases the strength and resilience of the webs and has the particular function or capacity of overcoming any tendency of the web to crack or weaken after creasing, folding or wrinkling. 25 Also, the binder employed is resistant to the action of oils and other household solvents, and does not disintegrate due to the action of moisture. When applying a rubber saturant, I may also use a bath or any of the other well known commercial methods employed for impregnating paper with latex. The rubber composition coating may be applied in any conventional way, for example, by coating rolls.

The web treated by immersion, as just described, has permanently and insolubly incorporated throughout its cellular structure, the flexible binder. This complete saturation is attained by reason of the interstitial nature of the web. 45 That is to say, the presence of the separator, i. e., the cork particles, and their interlaced relation with the fibres, produces cells, air spaces and voids, whereby the web exerts a maximum capillary effect and the fibres are impregnated and the cork particles coated. In fact, both the fibres and cork are encased in the binder, and the thorough permeation of the web assures the presence substantially uniformly throughout the web structure of sufficient binder to obtain and preserve the 50 qualities of strength, resilience and flexibility.

Examples of satisfactory binders are glutinous adhesives, such as casein, hide, bone, albuminous and similar glues capable of being rendered insoluble, and which can be treated or tanned, so as to become permanently and insolubly incorporated in the structure of the sheet. Other flexible binders which I employ in the cork fibre base are resin (natural and synthetic) and rubber 55 compositions, of which a great variety are commercially obtainable.

As tanning agents for the glutinous adhesives, I resort to one or more of such materials as formaldehyde, paraformaldehyde, hexamethylene-tetramine and sodium bichromate. In connection with the glutinous binder and tanning agent, I utilize plasticizers of which glycerine, diethylene glycol, and aquaresin, are examples.

I also make a rug holder consisting of a laminated paper-like web on a cylinder or multiple

Fourdrinier machine, one or more layers of said web being composed exclusively of fibres united during the paper-making process with one or more layers composed of cork and fibres, as disclosed in my U. S. Patent 1,888,410, issued November 22, 1932. This laminated structure has included therein a flexible binder as heretofore described.

In this manner, an acceptable rug holder is produced by using a core consisting exclusively of fibre in order to provide strength, and uniting to this core during the paper-making process, two outside layers of cork and fibre to contribute resilience and the tentacular surface effect. This web is permeated with a flexible, hygroscopic binder, such as glue, glycerine and formaldehyde.

The cork fibre web is impregnated with the binder during the saturating process. The amount of binder left on the surface or surfaces of the web is controlled according to the amount of excess saturant which is left on the surface after the bath immersion. By removing all of the excess practically no residual binder remains as a coating film. By varying the amount of excess binder remaining on the surface after saturation, the depth of coating is controlled. Likewise, the coating is applied in a separate process, that is, saturation is accomplished in a bath as described above and the coating of a material similar to or different from the saturant is applied by the customary means, as for example, by a set of coating rolls. For example, a cork and fibre web is saturated with glue, glycerine and formaldehyde and subsequently given a coating on one or both surfaces of a more concentrated glue, glycerine solution before the second tanning process. Again, a saturated cork fibre product is coated on both sides with a solution containing rubber, of which numerous varieties are commercially available, so that after drying the rug holder has a coating containing rubber on its surface. A coating composition is selected which is adapted to produce a surface which has anti-slipping or frictional qualities.

By such expressions as a solution containing rubber, rubber composition or rubber coating, I mean the use of solutions, binders or coatings which contain any natural India-rubber containing latex or any India-rubber containing latex preserved by ammonia, formaldehyde and the like, or any gutta-containing latex or balata containing latex, singly or combined. Likewise, I employ compositions of one or more of the above mentioned latices, with suitable vulcanizing agents, accelerators, activators, antioxidants and coagulants.

As previously mentioned, in some cases I increase the frictional resistance of the rug holder (whether its base is saturated with a binder or not) by providing its surface with a coating, covering or layer containing resilient particles, for example, comminuted cork or granulated rubber and obtain a particulated frictional contact surface. The particles are applied to a coating film with or without a subsequent sizing coat of binder to hold them firmly in place. Again they are applied by forming a mixture with the binder or coating film and applying such mixture to the surface of the base material. The binder employed to affix the cork particles is, in some cases, the same as that employed as the saturant. For example, glue, glycerine and formaldehyde, is used as a saturant and in more concentrated form to affix the resilient particles to the surface.

Likewise, the coating material containing the

resilient particles for some purposes is different from that used as the saturant. For example, glue, glycerine and formaldehyde is used as a saturant and a solution containing rubber is employed to affix the resilient particles to the surface.

While I prefer to affix the resilient particles to a base which contains a hygroscopic element, in some cases I use a base, such as drill cloth, and affix the particles, such as cork, to the cloth base by means of a coating which is hygroscopic, such as glue, glycerine and formaldehyde or other binders which are not essentially hygroscopic as I hereinafter define the term, such as solutions containing rubber.

It is an advantage of the cork fibre base that resilient cork particles are located on the surface during the paper-making process when the base material or web is formed which eliminates the necessity of affixing them by a subsequent coating process. The saturated cork fibre base, however, is in some cases provided with a coating, for example, one containing rubber or a coating containing resilient particles.

Throughout the specification and claims of this application, I have used the term "hygroscopic" to indicate a quality which is imparted to the rug holder by the employment of a saturant or coating which contains a hygroscopic ingredient or element. By "hygroscopic ingredient", I mean a material which, when included in a saturant or a coating, increases their moisture content beyond that which they would normally contain in equilibrium at any given humidity.

I prefer to use such an amount of a hygroscopic agent which at high humidities, namely, 85 or 90%, (to which levels the humidity frequently rises) will absorb a maximum amount of moisture and yet not sufficient to impair the frictional characteristics of the contact surface. At the same time, I use a sufficient quantity of the hygroscopic agent so that, at low humidities, namely, 25 to 30%, the rug holder will possess sufficient moisture so that it is flexible, resilient and has a high coefficient of surface friction. In other words, I employ an amount of a hygroscopic agent which will enable the rug holder to function satisfactorily at the humidities which it will encounter in actual service. That is, the hygroscopic agent is present in amount sufficient to render the rug holder constantly moist and provide a frictional contact surface.

The fundamental characteristics of the article of the present invention and the contribution of these characteristics to the successful application of the invention as a rug holder are as follows:

1. Strength and long life—In addition to possessing sufficient cross and length tensile, folding and tearing strength, the holders are wear and abrasion resistant and generally strong enough in all respects to withstand their normal usage and handling.

2. A high coefficient of friction to which the following factors also contribute.

3. Flexibility—which contributes to flat lying, easy handling, conforming to surfaces and the ability to withstand folding, bending, wrinkling, or sharp creasing without cracking or forming permanent lines of deformation. Likewise flexibility applies to the quality of the product which assists its return to its original state after such deformation as folding or wrinkling. The rug holders of this invention not only possess flexibility to a marked degree, but the ability to re-

tain this flexibility over a long period of time instead of becoming brittle and cracking or breaking.

4. Resilience meaning compressibility and rebound—Besides the inherent advantages of providing additional cushioning underfoot as well as sound adsorption and noise prevention, resilience in the rug holders of this invention contributes materially to the prevention of slipping.
- 10 When subjected to pressure, the surface of the resilient holder is forced into intimate engagement with the contiguous floor surface which, although polished, still contains myriads of surface scratches and other irregularities, indentations or protuberances. The resilient surface and/or body of the holder accommodates itself or conforms to the irregularities of level in the floor surface and the movement of the holder through or over these irregularities is impeded.
- 20 This effect is enhanced by the creation of irregularities of level on the resilient surface of the holder itself, which will mesh with, extend into, oppose and otherwise react with the irregularities of the floor surface. The maximum development of this effect is obtained by employing, for example, particles on the rug holder surface which are, in themselves, resilient, such as cork. It is understood, of course, that the cooperative relationship of the resilient rug holder with the 30 under surface of the rug will be similar to that with the floor just described.

Resilience implies the qualities of compressibility and rebound which enable the holder to compress readily and then return to its normal thickness and dimension after the force of compression has been removed. This ability is retained over long periods of time, which means that the product does not readily acquire a permanent set.

The resilience of the rug holder surface and especially the employment of resilient surface irregularities affords a tentacular effect. There is created, under pressure, a multitude of minute vacuum cups which effectively prevent movement of the holder on the floor.

45 5. A further important attribute of some of the rug holders of this invention is the ability to absorb and retain moisture, that is, it is hygroscopic. The retention of moisture augments the inherent flexibility and resilience of the holder and greatly increases the resistance against slipping. The presence of moisture contributes to the plasticity of the holder which causes it to flow and embrace a larger area of contact and better conform to contiguous surfaces which decreases 55 slippage.

6. Further desirable qualities are:

- (a) Resists disintegration by water, oil and other solvents commonly found in the household.
- (b) Freedom from marking, imprinting or otherwise damaging floor or rug surface.
- (c) Low cost and ease of commercial manufacture.
- (d) Ease of finishing or processing after fabrication, such as slitting or cutting.

65 In use, the rug holder is practically coextensive with the rug. In practically all cases, the rug holders as described possess sufficient strength, but, in some cases, I unite them with a reinforcing layer or backing, for example, cloth or paper, by means of a flexible binder or adhesive.

70 By "frictional contact surface" of a rug holder, I mean such a surface which resists movement over a contiguous floor or rug surface to an appreciably greater degree than the textile under- 75 surface of the rug. As previously described, I

produce a frictional surface on the rug holders of this invention in different ways. For example, (a) I include resilient particles, such as cork, or I include in the sheet structure a hygroscopic agent, such as a glycerine containing binder, or (b) I form the base and apply to it a frictional surface, such as a hygroscopic coating or a flexible coating containing resilient particles, such as cork or rubber.

10 In the drawing,

Figure 1 is a sectional view showing a rug holder A positioned between the rug and the floor;

Figure 2 is a modification of the rug holder shown in Figure 1, in section; and

Figure 3 is a modification of the rug holder 15 shown in Figure 1, also in section.

The several views of the drawing are representative of the rug holders described in this application, and for convenience, I have illustrated the floor at 10 and any suitable rug at 11. The 20 rug holder A shown in Figure 1 will be of any of the various structures described above in this specification and I have shown it as comprising a web which either has included therein a binder, or a web having one or more coatings applied to 25 its surface. In Figure 2, the base layer A is provided on its outer surface with particles adhesively united to the base as shown at 12. In Figure 3, one of the base layers described in this application is united to a preformed material such 30 as cloth, paper, all as described above.

I claim:

1. A rug holder comprising a separate layer adapted to be positioned between a floor covering and the floor comprising a resilient and flexible paper-like sheet of fibres and separators treated with a binder containing rubber, the said separators providing a particulated frictional contact surface.

2. A rug holder comprising a separate layer 40 adapted to be positioned between a floor covering and the floor comprising a resilient and flexible paper-like sheet of fibres and cork particles treated with a binder containing rubber, the said cork particles providing a particulated frictional contact surface.

3. An article to prevent the slippage of rugs, floor coverings or similar materials, on polished floors or other surfaces, which consists of a separate layer placed between the rug and the floor 50 and comprising a sheet material consisting of a paper-like base composed of cork and fibre and including a flexible binder, said comminuted cork providing a frictional contact surface.

4. An article to prevent the slippage of rugs, 55 floor coverings or similar materials, on polished floors or other surfaces, which consists of a separate layer placed between the rug and the floor and comprising a sheet material consisting of a paper-like base composed of cork and fibre and including a flexible binder and a flexible coating, said comminuted cork providing a frictional contact surface.

5. An article to prevent the slippage of rugs, 65 floor coverings or similar materials, on polished floors or other surfaces, which consists of a separate layer placed between the rug and the floor and comprising a sheet material consisting of a paper-like base composed of cork and fibre and including a flexible binder and a flexible coating 70 containing resilient particles providing a frictional contact surface.

6. A rug holder comprising a separate layer adapted to be positioned between a floor covering and the floor comprising a resilient and flex- 75

- ible base having a particulated frictional contact surface formed of particles of frictional material.
7. A rug holder comprising a separate layer adapted to be positioned between a floor covering and the floor comprising a resilient and flexible paper-like sheet of fibres and separators treated with a binder, the said separators providing a particulated frictional contact surface.
8. A rug holder comprising a separate layer adapted to be positioned between a floor covering and the floor comprising a resilient and flexible paper-like sheet of fibres and separators, the said separators providing particulated frictional contact surfaces upon opposite sides thereof.
9. An article of manufacture for preventing the slippage of rugs, floor coverings or similar materials on polished floors or other surfaces, which consists of a separate layer adapted to be placed between the rug and the floor which comprises a base of sheet material coated with a flexible binder and resilient particles.
10. An article to prevent the slippage of rugs, floor coverings, or similar materials, on polished floors or other surfaces which consists of a separate layer adapted to be placed between the rug and the floor and comprising a compressible sheet material which is treated with a flexible binder containing a hygroscopic agent in an amount sufficient to provide a frictional contact surface.
11. An article to prevent the slippage of rugs, floor coverings, or similar materials, on polished floors or other surfaces, which consists of a separate layer adapted to be placed between the rug and the floor and comprising a sheet material which is saturated with a binder rendering the article flexible and resilient, said binder containing a hygroscopic agent in amount sufficient to provide a frictional contact surface.
12. An article to prevent the slippage of rugs, floor coverings, or similar materials, on polished floors or other surfaces, which consists of a separate layer adapted to be placed between the rug and the floor and comprising a sheet material which is covered with a coating rendering the article flexible and resilient, said binder containing a hygroscopic agent in amount sufficient to provide a frictional contact surface.
13. An article to prevent the slippage of rugs, floor coverings, or similar materials, on polished floors or other surfaces, which consists of a separate layer adapted to be placed between the rug and the floor and comprising a sheet material which is saturated with a binder and covered with a coating rendering the article flexible and resilient, at least one said binder and coating having a hygroscopic agent present in amount to provide a frictional contact surface.
14. An article to prevent the slippage of rugs, floor coverings or similar materials, on polished floors or other surfaces, which consists of a separate layer adapted to be placed between the rug and the floor and comprising a sheet material which is saturated with a binder rendering the article flexible and resilient, said binder containing a hygroscopic agent in amount to provide a frictional contact surface, and said sheet provided with a coating forming a frictional contact surface.
15. An article to prevent the slippage of rugs, floor coverings or similar materials, on polished floors or other surfaces, which consists of a separate layer adapted to be placed between the rug and the floor and comprising a sheet material which is saturated with a binder rendering the article flexible and resilient, said binder containing a hygroscopic agent in amount to provide a frictional contact surface.
- rial which is saturated with a binder rendering the article flexible and resilient, said binder containing a hygroscopic agent, and said sheet provided with a coating of a material other than the saturant forming a frictional contact surface.
16. An article to prevent the slippage of rugs, floor coverings or similar materials, on polished floors or other surfaces, which consists of a separate layer adapted to be placed between the rug and the floor and comprising a sheet material which is saturated with a binder so that the article is flexible, resilient and hygroscopic, and provided with a flexible coating containing resilient particles, forming a frictional surface.
17. An article to prevent the slippage of rugs, floor coverings or similar materials, on polished floors or other surfaces, which consists of a separate layer adapted to be placed between the rug and the floor and comprising a sheet material which is saturated with a binder so that the article is flexible, resilient and hygroscopic, and provided with a flexible coating containing comminuted cork particles forming a frictional surface.
18. An article to prevent the slippage of rugs, floor coverings or similar materials, on polished floors or other surfaces, which consists of a separate layer adapted to be placed between the rug and the floor and comprising a sheet material which is saturated with a binder so that the article is flexible, resilient and hygroscopic, and provided with a coating containing rubber forming a frictional contact surface.
19. An article to prevent the slippage of rugs, floor coverings or similar materials, on polished floors or other surfaces, which consists of a separate layer adapted to be placed between the rug and the floor and comprising a sheet material which is saturated with a binder so that the article is flexible, resilient and hygroscopic, and provided with a coating containing rubber and resilient particles forming a frictional contact surface.
20. An article to prevent the slippage of rugs, floor coverings or similar materials, on polished floors or other surfaces, which consists of a separate layer adapted to be placed between the rug and the floor and comprising a sheet material which is saturated with a binder so that the article is flexible, resilient and hygroscopic, and provided with a coating containing rubber and comminuted cork particles forming a frictional contact surface.
21. An article of manufacture for preventing the slippage of rugs, floor coverings or similar materials on polished floors or other surfaces, which consists of a separate layer adapted to be placed between the rug and the floor which comprises a base of sheet material coated with a flexible binder which retains thereon resilient particles forming a frictional contact surface.
22. An article of manufacture for preventing the slippage of rugs, floor coverings or similar materials on polished floors or other surfaces, which consists of a separate layer adapted to be placed between the rug and the floor which comprises a base of sheet material coated throughout one surface with a flexible binder and comminuted cork particles.
23. An article of manufacture for preventing the slippage of rugs, floor coverings or similar materials, on polished floors or other surfaces, which consists of a separate layer adapted to be placed between the rug and the floor and comprising a base of sheet material coated with a

binder containing rubber and resilient particles forming a frictional contact surface.

24. An article of manufacture for preventing the slippage of rugs, floor coverings or similar materials, on polished floors or other surfaces, which consists of a separate layer adapted to be placed between the rug and the floor and comprising a base of sheet material coated with a binder containing rubber and comminuted cork particles forming a frictional contact surface.

25. An article to prevent the slippage of rugs, floor coverings, or similar materials, on polished floors or other surfaces, which consists of a separate layer placed between the rug and the floor and comprising a sheet material consisting of a paper-like base composed of separators and fibres treated with a flexible binder containing a hygroscopic agent in an amount sufficient to provide a frictional contact surface.

26. An article to prevent the slippage of rugs, floor coverings or similar materials, on polished floors or other surfaces, which consists of a separate layer placed between the rug and the floor and comprising a sheet material consisting of a paper-like base composed of comminuted cork and fibre and treated with a flexible binder containing a hygroscopic agent in an amount sufficient to provide a frictional contact surface.

27. An article to prevent the slippage of rugs, floor coverings, or similar materials, on polished floors or other surfaces, which consists of a separate layer placed between the rug and the floor and comprising a sheet material consisting of a paper-like laminated base in which one layer is composed exclusively of fibres and another of separators and fibres treated with a flexible binder containing a hygroscopic agent in an amount sufficient to provide a frictional contact surface.

28. An article to prevent the slippage of rugs, floor coverings or similar materials, on polished floors or other surfaces, which consists of a separate layer placed between the rug and the floor and comprising a sheet material consisting of a paper-like base composed of cork and fibre and including a flexible binder composed of tanned glue and a plasticizer, said comminuted cork providing a frictional contact surface.

29. A rug holder comprising a separate layer adapted to be positioned between a floor covering and the floor comprising a compressible and flexible paper-like sheet of fibres saturated with a binder, and having a frictional contact surface.

30. An article to prevent the slippage of rugs, floor coverings or similar materials on polished floors or other surfaces which consists of a separate layer adapted to be placed between the rug and the floor, and comprising a compressible sheet material treated with a flexible binder containing a hygroscopic agent in an amount sufficient to provide a frictional contact surface, said sheet having a particulated surface formed of particles also providing a frictional contact surface.

31. An article to prevent the slippage of rugs, floor coverings or similar materials on polished floors or other surfaces which consists of a separate layer adapted to be placed between the rug and the floor, and comprising a compressible sheet material of paper-like structure formed of

fibres and separators and treated with a flexible binder containing a hygroscopic agent in an amount sufficient to provide a frictional contact surface, said separators constituting a particulated frictional contact surface.

32. An article of manufacture for preventing the slippage of rugs, floor coverings or similar materials, on polished floors or other surfaces, which consists of a separate layer adapted to be placed between the rug and the floor and comprising a base of sheet material coated with a binder containing resin and resilient particles forming a frictional contact surface.

33. An article of manufacture for preventing the slippage of rugs, floor coverings or similar materials, on polished floors or other surfaces, which consists of a separate layer adapted to be placed between the rug and the floor and comprising a base of sheet material coated with a binder containing resin and comminuted cork particles forming a frictional contact surface.

34. A rug holder comprising a separate layer adapted to be positioned between a floor covering and the floor comprising a resilient and flexible paper-like sheet of fibres and separators treated with a binder containing a resin, the said separators providing a particulated frictional contact surface.

35. A rug holder comprising a separate layer adapted to be positioned between a floor covering and the floor comprising a resilient and flexible paper-like sheet of fibres and cork particles treated with a flexible binder, the said cork particles providing a particulated frictional contact surface.

36. A rug holder comprising a separate layer adapted to be positioned between a floor covering and the floor comprising a resilient and flexible paper-like sheet of fibres and cork particles treated with a flexible binder containing a resin, the said cork particles providing a particulated frictional contact surface.

37. A rug holder comprising a separate layer adapted to be positioned between a floor covering and the floor comprising a resilient and flexible paper-like sheet of fibres and separators treated with a binder, said sheet having a coating thereon of the same material as the binder and the said separators providing a particulated frictional contact surface.

38. A rug holder comprising a separate layer adapted to be positioned between a floor covering and the floor comprising a resilient and flexible paper-like sheet of fibres and separators treated with a binder, said sheet having a coating thereon adapted to provide a frictional surface and the said separators providing a particulated frictional contact surface.

39. A rug holder comprising a separate layer adapted to be positioned between a floor covering and the floor comprising a resilient and flexible paper-like sheet of fibres and separators treated with a binder, said sheet having a coating thereon of material different from the binder and adapted to provide a frictional surface, and the said separators providing a particulated frictional contact surface.

ELMER CLARENCE SCHACHT.
